UNITED STATES PATENT OFFICE

2,579,700

MACHINE FOR STRIPPING SHEET METAL

John Burley Picton, Wolverhampton, England,
assignor to Joshua Bigwood and Son, Limited,
Wolverhampton, England, a British company

Application July 5, 1950, Serial No. 172,101
In Great Britain July 11, 1949

7 Claims. (Cl. 242—81)

1

This invention relates to machines of the kind in which the sheet usually in the form of a coil, has its leading end engaged with a winding drum and is drawn through slitting tools which cut it into strips which are wound on the drum to form a plurality of individual coils disposed on the drum in side-by-side relationship.

In machines of this kind it is the usual practice when the strips have been coiled on the drum to bind the turns of each coil together while the coils are still on the drum to prevent them from unwinding. This practice necessitates leaving the coils on the drum while they are being bound, an operation which occupies a considerable time, and the primary object of the present invention is to provide means whereby the coils may be removed from the drum before they are bound so as to leave the drum free to receive the next slit coil.

According to the present invention, I provide a carriage mounted for movement parallel with the axis of the drum, the carriage having a body with an opening of approximately C-shape adapted to be moved over the coils on the drum and the body being provided for each severed coil with one or more inwardly movable gripping members whereby the coils can be prevented from unwinding when their ends leave the slitting tools, or other apparatus such as rollers the arrangement being such that the carriage can be moved to bring the body into a position in which it extends partially around the slit coils on the drum and the gripping member or members operated to engage the coils thereon, after which the coils can be operated on by a pusher so as to push them axially off the drum and to move the carriage axially so as to leave the drum clear for dealing with the next coil, the turns of the coils, now held in the body, being bound together by suitable means and the coils being then removed from the body.

The carriage which supports the body may be mounted on wheels which may run upon rails disposed parallel to the axis of the drum and means may be provided on the carriage for driving the supporting wheels for moving the carriage into the position in which the body is disposed partially around the drum.

The body may be provided with three grippers which are spaced angularly around the axis and which are disposed approximately radially thereto. These grippers may be angularly spaced around the axis so that they subtend an angle of more than 180°.

Each gripper may be operated by a piston and 55 admitted through a pipe 29. The admission and

2

cylinder actuated by pressure fluid from the same source and the bore of the middle cylinder may be somewhat less than the other two.

The pressure of the operating fluid may be controlled by means of a pump and regulated by means of valves.

The invention is illustrated in the accompanying drawings, wherein:

Figure 1 is a plan view.

Figure 2 is an end view.

Figure 3 is a side view.

Figure 4 is an enlarged section on line 4—4 of Figure 2.

Figure 5 is a section on line 5—5 of Figure 4.

Figure 6 is a section on line 6—6 of Figure 4.

In the construction illustrated the machine comprises a carriage having a frame 10 provided with a pair of supporting wheels 11 at each side. Each side of the frame may be formed by two

20 channel-section members 12 placed with the webs vertical and arranged side-by-side. These channels are provided with bearing blocks 13 in which the axles 14 of the supporting wheels, which may be of the flanged railway type, are mounted.

25 Rails 15 are provided on which the carriage can be run and these rails are parallel to the axis of the winding drum 16.

The carriage supports a body 17 which incorporates a pair of spaced plates 18 of approximately C-shape which are secured to spacing blocks 19. When the carriage is moved along its rails the body 17 partly encircles the coils 20 which have been wound or which are being wound on the winding drum 16 of the machine. The inner edge of the body extends around rather

35 more than one half of the peripheries of the coils but it is spaced therefrom. The gap between the ends 21, 22 of the body is sufficiently large to enable the coils 20 to be lifted out of the body by means of lifting gear and the gap is disposed at

40 the upper part of one side.

The spacing members 19 of the body are provided with radial openings in which are fixed three spaced cylinders 23 containing pistons 24. Each of the cylinders 23 is provided with an exterior flange 25 which is attached to a spacing member 19. Each cylinder at its outer end projects from the body 17 but its inner end is housed within one of the blocks 19. The outer end of

45 each cylinder is closed by a plate 26 to which a pipe 27 is connected so that pressure fluid can be admitted to the cylinder. Each cylinder is further provided with a passage 28 in the thickness of its wall to which passage pressure fluid can be admitted through a pipe 29. The admission and

exhaust of pressure fluid through the pipes 27 and 29 is controlled by a valve of known construction which is not shown in the drawings. Each of these cylinders 23 contains a piston 30 to which is connected a piston rod 31 extending through a gland 32 and the inner end of the piston rod is provided with a groove 33 engaged by a two part collar 34 attached to a sliding block 35. These blocks 35 are provided each with two pairs of shoulders 36 which are guided on facings 37 on the members 18. These facings are formed at the edges of radial slots 38 in the members 18. The edges 39 of these slots also assist in guiding the blocks 35. The inner end of each piston rod 31 is formed as a head 40 which is mounted in a recess 41 in one of the sliding blocks 35. Each sliding block at its inner end is provided with a dove-tail slot 42 extending parallel to the axis of the winding drum 16. Mounted in this slot are a number of finger plates 43 having dove-tail portions 44 and arranged side-by-side. Attached to the front and back faces 45 of each sliding block 35 is a plate 46. These plates being attached by screws 47. The finger plates 43 are clamped between the plates 46 by means of screws 48 on which are lock nuts 49. Distance plates 50 are provided between the inner faces of the plates 46 and the adjacent face of each outer finger plate. The finger plates 43 are shouldered at opposite sides so that their inner portions 45a are spaced apart axially while their outer portions 44 are in contact.

At their inner ends the finger plates are slotted axially at 46 so that each can receive at its inner end a wearing block 47 of relatively soft material, such, for instance, as wood or plastics material, the arrangement being such that these wearing blocks are adapted to be forced into contact with the outer turn of a coil.

The wearing blocks are shouldered at 48 and provided with ribs 49 at their outer sides which engage in the slots 46 in the finger plates and they are retained in position, each on a finger plate, by means of two screws 50.

A supply of pressure fluid is provided and this may be oil or other liquid or compressed air, the pressure being maintained by a pump and valves being provided so that admission of pressure fluid to the outer ends of the cylinders can be controlled and exhaust provided for when it is desired to release the pressure on the coils produced by the wearing blocks.

The three cylinders are spaced apart angularly around the axis and together they subtend an angle of more than 180° and the middle one of the three cylinders may be of somewhat smaller diameter than the other two.

Spaced rings 51 may be placed on the winding drum 16 between the coils and after the coils are pushed off the winding drum these spacer rings may be removed by moving them at right angles to the axis. Before the coils are pushed off the winding drum, the pressure fluid is admitted to the cylinders which control the gripping members causing the wearing blocks to move into contact with the outer periphery of each coil so as to prevent it from springing open.

The grippers are caused to grip the coils while the body is still in position over the winding drum and when this stage has been reached, the coils are pushed off the winding drum by the usual pusher causing the carriage 10 to move along its rails 15. As soon as the coils leave the winding drum the spacer rings can be removed. When the coils have been pushed off the winding drum

and the carriage moved away therefrom the winding drum 16 is left clear for a further winding operation and the turns of the coils now in the body can be bound or tied by means of clips or wire while they are in the body after which the gripper members can be released and the coils removed from the body.

What I claim then is:

1. A machine for removing coils of material from a winding drum, comprising a body of approximately C shape, said body being movable parallel to the axis of the drum, and power operated gripping means in the body for gripping the exterior of the coils, said gripping means being retractable to allow the coils to be removed from the body.

2. A machine for removing coils of material from a winding drum, comprising a carriage movable on rails parallel to the axis of the winding drum, a body of approximately C shape on said carriage so that the body can be moved from a position in which it partially encircles the winding drum to a position in which it is spaced from the end of the winding drum, and power operated gripping means in the body for gripping the exterior of the coils, whereby the coils can be gripped and withdrawn from the winding drum while held in the body, said gripping means being retractable to allow the coils to be removed from the body.

3. A machine for removing coils of material from a winding drum, comprising a body of approximately C shape, said body being movable parallel to the axis of the drum, a plurality of substantially radial cylinders in said body, said cylinders collectively subtending an angle greater than 180° around the axis of the winding drum, pistons in said cylinders, and piston rods connected to said pistons, said piston rods being each connected to a radially sliding block, carrying gripping means for the coil.

4. A machine for removing coils of material from a winding drum, comprising a body of approximately C shape, said body being movable parallel to the axis of the drum, a plurality of substantially radial cylinders in said body, pistons in said cylinders, and piston rods connected to said pistons, said piston rods being each connected to a radially sliding block, guiding means on the body for each of said sliding blocks, and a plurality of finger plates disposed side by side along the axial length of each block, said finger plates being clamped to said blocks.

5. A machine for removing coils of material from a winding drum, comprising a body of approximately C shape, said body being movable parallel to the axis of the drum, a plurality of substantially radial cylinders in said body, said cylinders collectively subtending an angle greater than 180° around the axis of the winding drum, pistons in said cylinders, and piston rods connected to said pistons, said piston rods being each connected to a radially sliding block, guiding means on the body for each of said sliding blocks and a plurality of finger plates disposed side by side along the axial length of each block, said finger plates being clamped to said blocks, and having their outer portions thicker than their inner portions, whereby the latter are spaced apart to permit of the use of spacing rings on the winding drum between the slit coils.

6. A machine for removing coils of material from a winding drum, comprising a body of approximately C shape, said body being movable parallel to the axis of the drum, a plurality of

substantially radial cylinders in said body, pistons in said cylinders, and piston rods connected to said pistons, said piston rods being each connected to radially sliding blocks, guiding means on the body for each of said sliding blocks, and a plurality of finger plates disposed side by side along the axial length of each block, said finger plates being clamped to said blocks, and wearing blocks secured to the ends of said finger plates.

7. The combination of a winding drum for winding side by side coils of metal separated by slits and a machine for removing the coils from the drum, the machine comprising, a carriage movable on rails parallel to the axis of the winding drum, a body of approximately C shape on said carriage so that the body can be moved from a position in which it partially encircles the wind-

10

15

ing drum to a position in which it is spaced from the end of the winding drum, and power operated gripping means in the body for gripping the exterior of the coils, whereby the coils can be gripped and withdrawn from the winding drum while held in the body.
